United States Patent Office

Des. 181,973
Patented Jan. 28, 1958

181,973

SHOE POLISH CONTAINER

Bruce B. Gordon, Glen Rock, and Emil W. Kimmig, Rutherford, N. J., assignors to Continental Can Company, Inc., New York, N. Y., a corporation of New York

Application April 6, 1956, Serial No. 40,945

Term of patent 14 years

(Cl. D58—11)

Fig. 1 is a side elevational view of a shoe polish container showing our new design;

Fig. 2 is a side elevational view thereof, partly in section, with the cover removed;

Fig. 3 is a bottom plan view thereof; and

Fig. 4 is a top plan view thereof.

We claim:

The ornamental design for a shoe polish container, as shown.
